UNITED STATES PATENT OFFICE.

HENRY W. FISHER, OF PERTH AMBOY, NEW JERSEY.

RETRIEVER FOR GOLF BALLS.

Application filed February 21, 1922. Serial No. 538,188.

To all whom it may concern:

Be it known that I, HENRY W. FISHER, residing at Perth Amboy, in the county of Middlesex and State of New Jersey, a citizen of the United States, have invented or discovered certain new and useful Improvements in Retrievers for Golf Balls, of which improvements the following is a specification.

10 My invention consists in a retriever for golf balls. In playing the game of golf the ball in play falls sometimes in such relatively inaccessible places as ponds, streams, and pits, with which the course is purposely 15 (or, it may be, accidentally) diversified, and my retriever is an instrument for the recovery of the ball from such places.

The retriever is illustrated in the accompanying drawings. Fig. I is a view in side elevation of the retriever in position ready to engage a ball, and of a ball, the retriever being in position relative to the ball to which it comes when about to engage the ball. Figs. II and III are views in side elevation 25 and to larger scale of the retriever closed upon a ball. These two views are on lines of sight at right angles, the one to the other, and Fig. II is on the same line of sight with Fig. I. Fig. II shows the stem or handle 30 of the instrument in longitudinal section.

The retriever consists essentially of a body 1 and a pair of jaws 2, 3 pivoted each of them to the body. The body may be of suitable shape and size; it ordinarily will be made of non-corrodible metal; the jaws are preferably made of metal also, and conveniently of loops of flat wire, as the drawings show. The loops which constitute the jaws are essentially circular (the circles being less in diameter than the diameter of the ball to be retrieved) and the ends of the loops form stems of the jaws, and they are pivoted to the body 1. The two jaws are pivoted to the body in such manner that the planes in which the loops severally extend are perpendicular to a common plane, and they stand, jaw opposite jaw. Being pivoted by their stems to body 1, the opposite loops may swing toward and from one another. All this formation is clearly shown in the drawings and with them in view the foregoing description will be clearly understood.

A spring or springs 4, 4 tend to hold the jaws in collapsed position in their mounting

on the body; that is to say, swung each toward the other, and, with a ball held between, in spring pressed engagement on opposite sides of the ball. This most clearly appears in Fig. II.

A toggle 5 is pivoted at its outer ends to the two jaws, the proportions being such that as the toggle is expanded the jaws will open, and as the jaws close the toggle will be collapsed; further, when the toggle is expanded to an extent slightly beyond its dead center (cf. Fig. I), its medial pivot point will lie between the now open jaws. A stop 6 limits the swing of the toggle in such direction. When the toggle has been expanded to this position the tension of the springs 4, tending to collapse the jaws, holds the toggle so expanded. When then, the parts being in the position shown in Fig. I, pressure is exerted upon the pivot point of the toggle sufficient in amount to swing the toggle in opposite direction (upward, Fig. I) across its dead center again, then the tension of springs 4, no longer resisted, collapses the jaws, and with them the toggle (to the position shown in Fig. II). The outer ends of the toggle being conveniently pivoted to the jaws approximately on the transverse diameter of the circular loops, are themselves shaped to corresponding curves. This clearly appears in Fig. III.

The operation is manifest. The instrument is set by swinging the toggle and expanding the jaws to the position shown in Fig. I. When in this position the instrument is caused to approach the ball to be retrieved (indicated at B in the drawings), and the pivot point of the toggle is brought to bear on the ball, and pressure is exerted, until the toggle is swung upward (Fig. I) across its dead center. Immediately the jaws close upon the ball, to the position shown in Figs. II and III; whereupon the ball may be lifted by the instrument from its place of inaccessible lodgment.

The instrument is carried on a stem or handle, such as indicated at 7 in the drawings. This handle may be jointed, after the manner of a fishing rod, and is indicated in Fig. I, and the joints may be of suitable length for carriage in a golf bag. The instrument itself may be permanently carried on the terminal joint of the handle; preferably it will be jointed thereto, as shown in

Fig. II, that being detached it may be slipped into a bag for carrying. Suitable provision may be made for bundling together the joints of the handle.

5 The retriever as thus far described may be rendered even more adaptable to conditions of service by mounting the body 1 through a stiff pivotal joint on a base 8, which base is directly borne on the stem or handle. The advantage of this detail is that on turning the instrument itself upon this pivot, out of line with the handle, it may be advanced upon the ball in direct line from above, while the user stands at a distance,—
10 15 say at the margin of a pond, in the middle of which the ball is lying.

I claim as my invention:

1. A golf ball retriever including in its structure opposite relatively movable ball-engaging jaws, a spring tending to hold the jaws in proximate ball-engaging position, and a toggle member pivoted at its opposite ends to said jaws and adapted when extended and holding the jaws in remote position, to be swung by pressure exerted upon the ball to be retrieved, allowing said spring
20 25

to swing the jaws to proximate ball-engaging position.

2. A golf ball retriever consisting of a handle, a body pivoted to and adjustable 30 in its position upon said handle, opposite ball-engaging jaws pivoted to said body and adapted to be swung yieldingly from proximate to remote relative positions, and means arranged between said jaws and adapted to 35 be rendered ineffective by pressure upon a ball to be retrieved for holding the said jaws in remote relative positions.

3. In a golf ball retriever the combination of a body, two loops of wire pivoted to said body, spring connection between said loops, and a toggle pivoted at its ends to the two loops and adapted when swung to and beyond its dead center to put said spring connection under tension and to stand itself 40 45 with its pivot point exposed between the expanded loops, said toggle being provided with a stop, substantially as described.

In testimony whereof I have hereunto set my hand.

HENRY W. FISHER.
